poration of America, a corporation of Dela-
ware

Application March 9, 1936, Serial No. 67,862

3 Claims. (Cl. 112—2)

This invention relates to upholstery forming machinery. More particularly, it relates to a specific type of upholstery forming machine adapted for the continuous preparation of padded upholstery panels for use in automobile seat backs and cushions.

The present invention contemplates the provision of a plurality of correlated units which are arranged together and synchronously operated in order to form unit upholstery panels. These upholstery panels comprise a pair of fabric members with a bat or stuffing layer of non-woven fibrous padding material secured in position therebetween to constitute padding for the panel as a whole. Panels of the general type with which the machinery of the present application is primarily concerned, usually constitute a backing sheet of woven fabric and a reveal section of finish fabric with a relatively thick bat of non-woven fibrous padding material, such, for example, as cotton linters disposed and secured in position therebetween. The two layers of fabric are preferably stitched together along spaced substantially parallel lines in order to secure the padding material in position therebetween and at the same time create a surface structure of substantially tufted effect for ornamental purposes.

The present invention in its principal embodiment contemplates the provision of apparatus for feeding a loosely felted layer of padding material between the two fabric layers and of automatic means for stitching the two fabric layers together with the padding material disposed therebetween, the stitching being performed along substantially parallel lines. The invention further contemplates means cooperating with the stitching means for pressing the two fabric layers closely adjacent each other just prior to the stitching operation in order to create the desired tufted or pleated effect.

An object of the present invention consists in the provision of measuring feed mechanism for feeding the fabric finish material, which measuring feed mechanism is operated synchronously with the mechanism for feeding the upholstery material through the stitching mechanism.

A further important feature of the present invention resides in the provision of mechanism which greatly facilitates the continuous operation of the apparatus as a whole in order to effect a great saving in the material used and a consequent saving in the cost of manufacture.

In furtherance of this last mentioned object, the present invention contemplates the provision of automatically operated means driven synchronously with respect to the remaining apparatus for feeding a loosely felted layer of non-woven padding material longitudinally through the apparatus as a whole. Means are further provided, in the event of breakdown of one of the auxiliary

units of the machine, for detouring this layer of felted non-woven fibrous material back, substantially to its source, in order that the mechanism which serves to feed the fibrous material need not be stopped during necessary interruption of operation of various other units of the machine. This feature of the invention is considered particularly important inasmuch as pad forming machines now available for the preparation of loosely felted fibrous materials are not susceptible of efficient 10 operation when frequent starting and stopping is required.

Still another particularly important object of the present invention consists in the provision of means associated with each of the stitching units, which means automatically serve to actuate mechanism for cutting off and detouring the padding material in the event that one of the threads feeding to the stitching machine breaks. This construction provides one in which the feed of 20 the fabric material, as well as feed of the padding, is automatically stopped in the event that there is a breakdown of any one of the stitching units.

Still further the present invention contemplates the provision of fabric finish layers of material in which the lateral side edges thereof are cut to substantially the final desired form before the fabric finish material is assembled with respect to the remainder of the upholstery panel. Inasmuch as only the lateral side edges are cut to form prior to the assembly of the panel, it will be appreciated that the fabric finish material is retained in a relatively long strip and may be handled in substantially the same manner as a continuous strip of material on which no cutting operations 30 have been performed.

Many other and further objects, advantages and features of the present invention will become apparent from the following specification when considered in connection with the accompanying 40 drawings forming a part thereof.

In the drawings:

Figure 1 is a fragmentary, perspective view with parts in section illustrating a seat construction upholstered with the improved upholstery 45 panel manufactured by the machine and in accordance with the method of the present invention.

Figure 2 is a sectional view, taken substantially on the line 2—2 of Figure 1, illustrating in detail the tufted upholstery finish panel manufactured 50 in accordance with the method and the machine of the present invention.

Figure 3 is a perspective view, showing the completely assembled upholstery forming apparatus with the various units thereof arranged in operative relation with respect to each other.

Figure 4 represents, in plan, the strip of fabric finish material which is fed into the machine for 60

the purpose of providing a finish for the upholstery panels formed thereby.

Figure 5 is a plan view of a different form of continuous strip of trimmed fabric finish material.

Figure 6 is an enlarged perspective view of the central unit of the machine in which the layers of fabric material are fed on either side of the sheet of felted non-woven fibrous padding material and the three members stitched together in unit relation.

Figure 7 is a fragmentary, perspective view, partly in section, taken on the line 7—7 of Figure 6, illustrating one of the trackways for mounting the carriages supporting the rolls of backing fabric.

Figure 8 is a vertical, longitudinal, sectional view of the unit of the machine shown in Figure 6, illustrating in detail the various feeding mechanisms therefor and the relative positions of the parts thereof.

Figure 9 is an enlarged, fragmentary, sectional view, illustrating in detail the cut-off mechanism which serves to interrupt the feed of the padding material in the event of breakdown of any of the units of the stitching mechanism.

Figure 10 is a fragmentary, sectional view, similar to Figure 9, showing the cut-off mechanism after it has completed a severance of the felted bat.

Figure 11 is an enlarged, fragmentary, perspective view of one of the stitching units and also showing the individual tuft forming and feed mechanism associated therewith.

Figure 12 is a sectional view, taken substantially in the line 12—12 of Figure 11, illustrating the mounting of one of the sprockets of the tuft forming and feed mechanism.

Figure 13 is a fragmentary plan view, illustrating the pleat forming and fabric feed mechanism showing the manner in which the pleat forming chains converse toward each other to produce the required pleat fullness.

Figure 14 is an enlarged, sectional view, taken substantially on the line 14—14 of Figure 13, illustrating the manner in which the finish fabric is fed into engagement with the padding material.

Figure 15 is an enlarged, fragmentary, sectional view, taken substantially on the line 15—15 of Figure 13, illustrating the manner in which the pleats or tufts are formed.

Figure 16 is a fragmentary, perspective view, illustrating a modified form of tuft forming mechanism which operates directly upon the padding material prior to the application of the finish material.

Figure 17 is an enlarged, fragmentary, sectional view, taken substantially on the line 17—17 of Figure 16, showing in detail the inter-engaging rollers which serve to form tufts in the padded material.

Figure 17a is a sectional view, illustrating the form of the padding material after it has been subjected to the action of the mechanism shown in Figures 16 and 17.

Figure 18 is a fragmentary, perspective view of a still further modified form of tuft forming mechanism in which the padding material is partially severed along substantially longitudinal lines.

Figure 19 is an enlarged, sectional view, taken substantially on the line 19—19 of Figure 18,

showing in detail one of the cutter wheels and its engagement with the padding.

Figure 20 is a circuit diagram, illustrating the automatic means for controlling the feed of the padding mechanism in the event of breakdown of one of the stitching units.

Figure 21 is a side elevational view of the upholstery forming unit of the machine illustrating the drive mechanism therefor and the manner in which the respective parts thereof are correlated.

With more particular reference to the drawings, it will be appreciated that the specific embodiment of the invention illustrated therein and described below, relates to the formation of upholstery trim panels such as are conventionally used in the formation of vehicle seat cushions and seat backs substantially of the type illustrated in Figure 1. Cushion constructions of this generic type generally comprise a rectangular framework 10 serving to support a plurality of coil springs 11. The upper ends of the coil springs are preferably covered with a layer of burlap or other fabric backing material 12 to which is applied a suitable layer of padding 13. The upholstery trim panels with which the present invention is primarily concerned are applied directly over the layer of padding 13. These panels, it will be seen, comprise a backing layer 15 of suitable woven fabric material and a finish layer 16 of woven material adapted to provide an attractive finish for the seat construction and an intermediate layer of non-woven fibrous material such, for example, as cotton linters secured between the fabric layers 15 and 16. The layers of fabric material 15 and 16 are preferably secured together along substantially parallel spaced lines, by stitching 18 to form an attractive tufted or pleated exterior surface, which lines of stitching also serve the purpose of retaining the non-woven felted cotton linters in position between the two fabric layers.

The apparatus of the present invention is primarily concerned with the provision of means for automatically and continuously forming upholstery panels such as are shown in the sectional view in Figure 2.

In Figure 3 is illustrated the complete assembly of one embodiment of the mechanism provided by the present invention for the continuous formation of upholstery trim panels such as have been described above.

The layout unit which is seen in the lower left-hand portion of Figure 3 is shown as placed in line with the remainder of the apparatus, but the position of this unit is not particularly important inasmuch as it does not, in fact, physically cooperate with any of the remaining units of the machine. This layout unit is utilized for the purpose of preparing continuous strips of fabric finish material for utilization in the upholstery forming mechanism of the apparatus described in detail below. This layout unit comprises a work table 20 of substantial longitudinal length which has a flat top 21 of a width slightly wider than the fabric finish trim material to be prepared. Securely mounted in spaced relation at each end of the lateral sides of the top 21 are longitudinally extending trackways 22 which serve to provide means for movably mounting a layout carriage 23, the construction and operation of which is described in detail in applicant's assignee's prior co-pending application, Serial No. 68,161, filed March 11, 1936.

As will be clear by reference to this prior co-pending application referred to above, the car-

riage 23 provides means for mounting a pair of rolls 24 of fabric finish material. Means are provided upon the carriage for automatically moving the carriage longitudinally with respect to the work table 20 on which it is mounted. The carriage includes thereon measuring feed mechanism to unroll cloth from the rolls 24 and lay it out upon the table in flat, uniform, superimposed layers 25. A suitable weight 26 may be utilized for the purpose of maintaining these strips of fabric material in predetermined superimposed relation and after a suitable number of layers have been stacked one upon another, the entire stack is trimmed by means of an electrically operated cutter 27 to form the lateral edges of the finish material to the desired configuration. As will be clearly seen by reference to Figures 4 and 5, the lateral edges of the strips of cloth are trimmed to provide a configuration substantially as will be desired in the lateral edges of the finished upholstery panels while the panels as a whole are not trimmed at their top and bottom edges; consequently, it will be seen that after the trimming operation has been performed, the fabric finish material will still retain its continuity as a single integral strip of cloth which may be rewound by the traveling carriage 23 in substantially the same manner in which it was unwound and laid upon the table. After the fabric finish material has been laid out and has had its lateral edges trimmed, the finish material is rewound into a roll 28 of substantial diameter and supported in bearings upon the upholstery forming mechanism hereinafter described in detail.

The mechanism for automatically preparing and forming a continuous bat of loosely felted, non-woven cotton linters for utilization as padding in the upholstery panels is shown in Figure 3. This mechanism preferably comprises a pair of Garnett machines 30 and 31 which are preferably disposed side by side at the lateral side of the apparatus as a whole. These machines are substantially conventional in construction and cotton linters or other suitable similar non-woven fibrous material may be fed thereinto and will be combed and beaten until the fibers are distributed substantially at random and fed from these machines upon a pair of endless conveyor belts 32 and 33, respectively, which feed this bat to a second pair of reciprocably mounted conveyors 34 and 35, which extend over the main feed mechanism of the apparatus hereinafter described in detail.

As is conventional in structures of this kind, a plurality of trackways 36 extend transversely of the apparatus as a whole and serve to provide means for movably mounting the forward end of the endless conveyors 34 and 35. Suitable means, not shown, such as is conventional in the art, may be provided for automatically reciprocating the forward ends of the conveyors 34 and 35 back and forth along the trackways 36 in order that the loose non-woven fibrous material will be fed therefrom in a substantially uniform, matted layer upon a longitudinally extending conveyor belt 37 mounted in a suitable longitudinally extending framework 38. It will be appreciated that the construction described above serves to provide a felted bat 39 of padding material leaving the pad forming unit on the belt 37, and it will be clear that the thickness of this padding material may be accurately regulated by regulating the rate of operation of the pad

forming machines 30 and 31 with respect to the rate of travel of the conveyor belt 37.

It will be seen by reference to Figures 3, 5, 8, 9 and 10 that the conveyor belt 37 serves to move this bat or uniform layer of fibrous padding material up into and feed the same into the rear end of the upholstery forming mechanism hereinafter described in detail.

As will be seen clearly by reference to Figures 9 and 10, the forward end of the conveyor belt 37 passes over a suitable roller 40 which cooperates with a roller 41 serving to compact and compress the bat into a layer of padding of substantially uniform thickness in order that the subsequent operations hereinafter described may more easily be performed thereon.

The upholstery forming unit, best seen in the perspective view, Figure 6, and sectional view, Figure 8, comprises a pair of suitable side frame members 45 and 46 which serve to provide fixed supports for journaling the rollers 40 and 41 as well as numerous other shafts, conveyors and mechanism hereinafter described in detail. The upholstery forming unit is provided substantially throughout its body portion with a fixed plane surface work table 50 extending throughout substantially the entire width thereof. A pair of housings 51 are provided underneath this work table adapted to receive rolls 52 of backing cloth. These rolls 52 are preferably journaled for rotation in carriages 53 provided with suitable flanged wheels 54 adapted to run in trackways 55 which may be formed substantially in the floor level such as is shown in detail in the fragmentary perspective view, Figure 7.

It will be appreciated that the above described construction permits the installation of two rolls of backing cloth in the upholstery forming machine, only one of which is fed into the machine at a time. It will be apparent that when one roll is nearly exhausted, the leading end of the cloth material on the other roll may be connected thereto and fed directly into the machine, thus preventing the necessity of stopping the mechanism during the connection of a new roll of cloth. The structure provided makes the substitution of a new roll for an exhausted one a relatively simple operation which may be accomplished without in any way disturbing the operation of the machine.

As may clearly be seen from the sectional view, Figure 8, the cloth is unwound from the roll 52 and passes upwardly around an idle roller 57, the upper peripheral surface of which lies substantially in the same plane as the surface of the table 50. The cloth passes around this roller 57 and along the table toward the stitching unit, which is described in detail below.

It will be apparent that the matted felted layer of fibrous material 39, as it is fed into this upholstery forming unit, will be fed in on top of this layer of backing material and will be carried along the work table 50 thereby into the stitching mechanism.

A shield 58, arranged substantially parallel with the work table 50, and spaced thereabove, serves to maintain the bat 39 in engagement with the backing material 52 as it passes along the work table 50 and it will be noted that this shield 58 is flared at its rearward end 59 to facilitate the entry of the padding material between the work table and the shield.

The roll of fabric finish material 28, which has its lateral edges cut to form as described above, is mounted upon a pair of supports 65 extending

upwardly from the side frames 45 and 46 of the upholstery forming unit. These supports 65 are provided at their upper ends with suitable bearings 66 which serve to support a shaft running axially through the roll 28 to permit free rotation thereof with respect to the frames in which it is mounted. This shaft is also adapted to seat on the reel supporting members in the lay-out mechanism described in the prior co-pending application referred to above. An endless belt 67 is mounted upon a plurality of transversely extending freely rotatable rollers 68, which are positioned in such a manner that the belt 67 will resiliently engage a substantial portion of the peripheral surface of the roll of fabric finish material 28. In order to effect engagement of the belt 67 with the roll 28 at all times, irrespective of the diameter of the roll, a pair of arms 70 are pivotally mounted on each of the side frames 45 and 46 and serve to provide in their upper ends means for rotatably mounting an idle roll 71. These arms 70 have portions 72 which extend past the pivot point of the arms and each has secured thereto one end of a tension coil spring 73 which serves to urge this roller 71 into engagement with the roll of fabric finish material 28 at all times and serves to aid in maintaining the belt 67 properly resiliently tensioned irrespective of the diameter of the roll of cloth 28. In addition, the belt 67 may be tensioned by a second roll 75, journaled for rotation in the ends of a pair of arms 76 which are pivotally mounted on the frames 45 and 46 at a point 77 intermediate the ends of the arms. The opposite ends of these arms provide means for attaching the opposite end of the coil spring 73 described above.

From the foregoing, it will be clear that the rolls 75 and 71, together with their pivotal mounting arms, and the tension coil springs 73, serve to maintain the belt 67 properly tensioned at all times irrespective of the diameter of the roll of cloth which it engages.

Cloth may be fed from the roll 28 down along the conveyor belt 67 and on to a frame comprising a plurality of longitudinally extending, converging, upwardly presenting channel members 80. These channel members may be maintained in predetermined relative position by means of suitable transversely extending frame members 81, one of which is shown in Figure 11. The framework as a whole slopes generally downwardly and forwardly in order that cloth carried on the surface thereof will be brought gradually down and delivered into engagement with the felted padding material 39 which, as has been explained above, lies on top of and is carried along by the backing sheet 52 on top of the work table 50.

When the roll of fabric finish material 28 is approaching exhaustion, a second roll of this material is swung adjacent thereto by means of a suitable overhead crane and the terminal end of the fabric finish strip 28 is secured to the leading end of the new roll and the new roll is then mounted in position, thus providing an uninterrupted and constant supply of fabric finish material to the machine. From the foregoing it will be appreciated that the machine as a whole may be operated continuously and without interruption for as long a period as may be desired.

A framework, generally designated as 90, is pivotally mounted upon a shaft 91 extending transversely of the conveyor system as a whole and is adapted to be swung down into engagement with the channel framework 80. The framework 90 has a shaft 92 rotatably mounted therein at

the end thereof opposite to the end at which it is pivoted, and it will be seen by reference to Figure 13 that a plurality of sprocket wheels are permanently secured to each of the shafts 91 and 92. Sprocket chains 95 extend between each of the sprocket wheels 93 and 94, and it will be appreciated by reference to Figure 13 that the sprocket wheels 93 on the shaft 91 are considerably more closely spaced than the sprocket wheels 94 on the shaft 92. Consequently, as the chains 105 approach the forward end of the frame, they become closer and closer together. It will be seen by reference to Figure 11 that one of these sprocket chains is positioned to cooperate with each of the upwardly presenting channel members 80 in the framework over which they lie. As is conventional in structures of this kind, a take-up or idler roller 96 may be journaled in one end of a suitable pivoted bell crank 97, the opposite end of which is controlled by a spring 98 to maintain the sprocket chains tight at all times. The blocks between adjacent links in the sprocket chains 95 are provided with outwardly projecting, sharply pointed pins 100, which, it will be seen, serve to extend into the channel member 80 with which the chain cooperates. Each of the sprocket chain assemblies may be covered by a suitable sheet metal housing 101, as may be desired, and, as is clear by reference to Figure 11, this housing may serve to provide means for pivotally mounting the bell crank member 97 of the take-up mechanism.

The shaft 91 is rotated by means hereinafter described in detail to simultaneously drive all of the sprocket wheels 93 thereon and consequently drive the sprocket chain 95 carried thereby. It will be appreciated that as the finish fabric material 25 is fed in on top of the framework 80, the projecting pin 100 will project through the material and move this material along the framework at a rate corresponding exactly with the rate of speed at which the sprockets 93 are driven. Due to the fact that the channel members 80 slope gradually downward, it will be apparent that this material will be gradually brought into close proximity with the upper surface of the padding layer 39, which, as has been described above, is disposed on top of the fabric backing sheet of material on the work table 50. Due to the convergence laterally 40 toward each other of the channel members 80 and their cooperating sprocket chains, it will be seen that the fabric finish material is brought laterally inward in order to provide the excess thereof required for the desired pleat fullness. 55

The three superimposed layers, namely, the backing sheet, padding layer, and the fabric finish material, pass from the upholstery forming unit to the stitching unit, also shown in the sectional view, Figure 8. This stitching unit comprises a pair of laterally spaced frames 105, located on either side of the work, having mounted therein a roller 106 which serves to support the rear end of a conveyor belt 107, the upper surface of which belt, it will be seen, lies substantially in the plane of the work table 50 of the upholstery forming machine. A feed roll 108 is driven by means hereinafter described, upon a transverse axis and is preferably urged by 70 means of springs 109 into engagement with the upper surface of the conveyor belt 107. It will be seen that these cooperating rollers 106 and 108 serve to feed the material through the sewing mechanism and draw the material also 75

through the upholstery forming unit described above.

A plurality of sewing machines of substantially conventional form are arranged in spaced relation transversely across the line of travel of the work. The sewing machines making up the stitching unit preferably comprise a plurality of vertically disposed needles 110, operated by rods 111, actuated by a transversely extending cam shaft 112 common to all of the sewing machines. Each of the needles 110 may be supplied with a suitable source of thread 113. Beneath the work table, the machines are provided with conventional loopers 114 for cooperating with the needles 110 and this lower assembly may also be supplied by a separate source of thread 115.

The sewing machines are spaced laterally from one another in accordance with the spacing of the sprocket wheels 93 on the shaft 94 and each sewing machine is provided with a forwardly extending foot 120, which is preferably resiliently mounted for vertical movement and urged downwardly toward the surface of the work table by means of a compression coil spring 121. This forwardly extending foot is preferably bifurcated at its forward end to provide an upturned fork 122, which extends on either side of the sprocket chain with which it cooperates. It will consequently be apparent that material fed forwardly by the sprocket chains will be forced in underneath the foot, and due to the curvature of the foot will be forced downwardly and separated from the pins in the chain and closely into engagement with the upper surface of the work table over which the material is travelling. It will be apparent that this foot structure serves to compress the loose fibrous material between the fabric finish layer and the backing sheet, and due to the fact that the fabric finish layer has been gathered in by the converging sprocket chains 95, sufficient finish material will be available to provide the necessary pleated or tufted effect, and consequently the fabric finish layer may be stitched by each of the sewing machines closely into engagement with the backing sheets along longitudinally extending parallel lines.

From the foregoing, it will be apparent that a continuous composite upholstered strip will be fed outwardly along the conveyor belt 107 from the stitching unit. This composite strip will comprise a backing layer and a fabric finish layer with the padding or upholstery therebetween and these members will all be secured together along substantially longitudinal lines providing longitudinally extending tufts or pleats.

Referring again to Figure 3, it will be clear that, as this material leaves the stitching unit, it may be fed outwardly onto a work table 120, where the strip may be severed to provide separate individual upholstery panels 121. These adjacent panels may be cut from one another by means of a suitable electrically operated cutting mechanism 122, similar in construction and operation to the cutter 27 referred to above.

As has been explained above, the two rolls of backing material located in the housing 51 underneath the work table 50 provides structure whereby a continuous web of backing material may be fed into the machine and it will be appreciated from the above description that the Garnetting machines 30 and 31 serve to provide a continuous web of loosely felted cotton linters providing a padding web between the backing and finish layers of the upholstery panels.

It is, however, inevitable that the stitching unit must be stopped from time to time in order to repair broken threads or broken needles and adjust the mechanism thereof. Consequently, the present invention contemplates the provision of automatic means for immediately arresting the movement of the padding material through the upholstery forming unit, cutting off the back of padding material being fed therewith, and detouring this cut-off portion away from the upholstery forming unit in order that the Garnett machine and pad forming mechanism will not have to be stopped during the time when it is necessary to stop the operation of the stitching unit. This is accomplished by means of a hydraulic cylinder 131 actuated by means herein-after described in detail.

The cut-off mechanism preferably comprises a transversely extending table 135, the upper surface of which lies substantially in the plane of the work table 50 described above. A pair of end sectors 136 are pivotally mounted upon the axis of the roller 40 and these sectors have extending therebetween a table section 137 which is normally, during operation of the machine, adapted to lie in the same plane as the transversely extending table 135. The transversely extending operating rod 132 is directly connected to the sectors 136. It will be seen that vertical movement of the piston of the hydraulic cylinder construction 131 will serve to cause simultaneous pivotal movement of the sectors 136 about their pivot point and consequently will serve to move the table structure 137 arcuately downwardly with respect to the plane of the work tables 135 and 50. The sectors 136 are also interconnected by means of an arcuately curved blade mounting member 140, in which is mounted a transversely extending cutter blade 141, which serves to cooperate with the rear edge of the table 135 to provide a shear for cutting off the forwardly moving strip of padding material 39, when the sectors 136 are moved arcuately about their pivots by the hydraulic cylinder construction 131. A pair of brake arms 144 are mounted for pivotal movement about the axis of rotation of the roller 41. These arms are disposed on opposite sides of the upholstery forming unit and have extending therebetween a brake shoe 145, which serves to cooperate with the upper surface of the table 135 to arrest movement of the fibrous padding material when the operation of the stitching mechanism is interrupted. This brake assembly is at all times urged toward the table 135 by means of a tension coil spring 146, which may be anchored to the framework.

The transversely extending knife supporting bar 140 has, on the upper surface thereof, a pair of brackets 147 which serve to support rollers 148 adapted to contact the arcuately curved underside of the brake arm 144. The under-sides of these brake arms 144 are preferably curved to provide a cam surface 149 of such curvature that when the sectors 136 are swung downwardly to cut off the padding material, the brake arm will be permitted to move downwardly, thus clamping the padding material between the brake shoe 145 and the upper surface of the table 135. It will be apparent from the above described construction that when the sewing machine is stopped, actuation of the hydraulic cylinder 131 will move the arcuate sectors 136 downwardly. This downward movement will cause the apparatus to assume substantially the position shown in Figure 10 of the drawings.

It will be seen by reference to this figure that

the web of padding material has been cut off and the forward end thereof is directed downwardly underneath the table 135 and it will be seen that, as further forward movement of this padding material takes place, it will be fed into contact with the arcuately curved shield 150, which will serve to direct this bat or strip of padding material downwardly onto a conveyor belt 152 disposed underneath the conveyor belt 37 in the frame of 5 the pad forming mechanism. It will be apparent that during the time the sewing machine is stopped, the Garnett machines 38 and 39 may remain in operation and the padding material generated thereby will be fed onto the conveyor belt 152 from whence it may be moved and returned to the Garnett machine. The upper edge of the shield 150 is bent downwardly and sharpened to form a transversely extending knife edge 155 which serves to cooperate with the forward edge 10 of the table portion 137 to again cut off the web of padding material when the sector members 136 are returned to their normal position. It will be apparent that when the sector members 136 are urged upwardly to the position shown in 15 Fig. 9, the web of padding material 29 will be cut off by the knife edge 155 and this cut off end portion will be brought directly into engagement with the butt end of the strip of padding material which has been retained in the upholstery forming mechanism by the brake shoe 145.

It will further be apparent that upward movement of the sectors 136 will cause the brake shoe 145 to be raised from the padding material in the upholstery forming machine and consequently 20 permit the resumption of forward movement thereof with the forward end of the padding material being fed in in closely abutting relation with the rear end of the padding material which has been retained in the upholstery forming machine 25 during the interruption of the operation thereof.

It is highly desirable that the conveyor 106, which feeds the completed strip from the machine, the sprocket chains 95 which feed the finish material into the apparatus, the conveyor 67 30 which feeds the finish material to the sprocket chains, and the conveyor 37 which feeds the padding material into the upholstery forming machine, be all run at a speed which will produce a substantially uniform rate of travel of all of 35 the relative members longitudinally with respect to the apparatus as a whole.

As has been explained above, the rate of operation of the Garnett machine should be carefully proportioned with respect to the rate of travel of 40 the conveyor 37, in order to effect the creation of a layer of padding material of the desired weight and thickness, and it is consequently desirable that the Garnett machines be operated in synchronism with the remainder of the apparatus.

In certain instances, it has been found desirable 45 to preform the padding material prior to its insertion between the fabric finish sheet and the backing sheet in order that the tufts therein will be substantially preformed prior to its insertion between the fabric finish layer and the backing sheet. In Figures 16 and 17 of the drawings, I 50 have illustrated one form of mechanism which may be utilized for accomplishing this result. It will be appreciated that the mechanism herein- 55 after described may be inserted into the above described system at any suitable point past which the formed padding material passes prior to its insertion between the backing sheet and the fabric finish layer. In the specific embodiment of 60 75 the invention shown in the drawings, the ap-

paratus is shown as mounted just forwardly of the table section 135. A transversely extending shaft 170 is provided with a plurality of spaced forming wheels 171. These wheels are spaced apart on the shaft in accordance with the spacing of the lines of the stitching in the resultant panel structure. The bat 172 is fed in between these wheels and cooperating grooved wheels 173, mounted for rotation on a shaft 174 beneath the level of the table. The grooved wheels 173 may be provided with upstanding circumferentially extending cutting edges 175 in the base of the groove in order to cut or tear the fibrous material in the lower side thereof to facilitate the distribution of this fibrous material by the forming rolls 171. The configuration of the bat 172 resulting from the forming of this structure is shown in the sectional view in Figure 17a.

A still further modified form of construction is 20 illustrated in Figures 18 and 19. It will be seen that this apparatus is preferably mounted over the work table 50 after the padding material has been fed in on top of the backing web. A transversely extending shaft 180 is provided with a plurality of spaced, circular cutters 181 which 25 serve to cut the strip of padding material partially through along longitudinal lines spaced apart in accordance with the spacing of the stitching mechanism by which the fabric finish layer is secured to the backing web. A transversely extending shaft 182 may be provided adjacent the shaft 180 and may carry thereon a plurality of rotary sharpening elements 183 which may be urged into engagement with the knives 181 when it is desirable to sharpen the same. Transversely extending shafts 185 and 186 may be disposed in front of and behind the shaft 180 carrying the cutters and these shafts may carry a plurality of pulleys 187 and 188, respectively, which serve to mount feed belts 189, operated in synchronism 30 with the rate of travel of these backing sheets and padding material through the mechanism. It has been found that partially severing the padding material along longitudinal lines serves to greatly facilitate the formation of the tufted or pleated 35 structure.

The specific manner in which the upholstery forming unit is synchronously driven and controlled is best understood by reference to the circuit diagram of Fig. 20 and the diagrammatic side 40 elevational view of Figure 21. The entire upholstery forming unit is driven by means of an electric motor or other source of power 200, which is preferably mounted in the frame of the stitching mechanism. This motor has secured thereto 45 a gear 201, which by means of a sprocket chain 202, serves to drive a gear 203 secured to a transversely extending shaft 204 journaled for rotation in suitable bearings in the side frame 105 of the stitching unit. The shaft 204 has at each of its 50 ends, pulleys 205 secured thereto, which serve to drive belts 206 which run over pulleys 207 secured to the opposite ends of the cam shaft 112 which serves to operate the stitching needles.

As is conventional in constructions of this kind, 55 the belt may be maintained taut by means of a suitable idle pulley or roller 208 journaled in the end of a pivotally mounted arm 209 and resiliently urged into engagement with the belt 206 by means of a suitable spring 210. It will be appreciated 60 that the relative diameters of the pulleys 205 and 207 may be varied in order that the speed at which the cam shaft 112 driving the stitching mechanism is rotated may be controlled within 65 desired limits.

A bevel gear 215 is secured to the cam shaft 112 and serves to drive a bevel gear 216 secured to the upper end of a vertically extending shaft 217. The lower end of this shaft 217 also carries a bevel gear assembly which serves to drive a pinion 218 which meshes with a second pinion 219 secured to a suitable transversely extending shaft for operating the looper mechanisms which cooperate with the various needles.

10 In its central portion the shaft 217 is provided with a sprocket wheel, which serves, by means of suitable sprocket chain 220, to drive a sprocket wheel on the upper end of a second vertically extending shaft 221. The lower end of this shaft 15 221 has secured thereto a worm 222 which meshes with a worm wheel 223. The worm wheel 223 is secured to the shaft of the roller 106 which serves to operate the conveyor 107. Also secured to this shaft is a large gear 225 which meshes with a 20 second large gear of equal size 226 carried by the roller 108.

From the above described structure, it will be apparent that the electric motor 200 serves to drive the needle operating mechanism by means 25 of a belt 206. It will further be appreciated that the drive of the conveyor operating roller 106 and the feed roller 108, which together serve to draw the upholstery material through the upholstery forming unit, are positively driven in synchronism 30 with the sewing machines and the various gearing elements are so proportioned that the speed of this mechanism will be synchronous with the rate of speed of the sewing machine itself. The shaft of the roller 106 also has secured thereto a 35 sprocket wheel 230, which, by means of a sprocket chain 231, serves to drive the shaft 91 which actuates the measuring feed mechanism for the finish material. Consequently, it will be apparent that this mechanism also is operated synchronously with the feed rollers 106 and 108. 40 Power from this same source may be utilized to drive the measuring feed belt 67 which delivers the fabric finish material to the pleat forming mechanism and this drive may be accomplished by means of a suitable sprocket chain 235 which drives a sprocket 236 secured to the shaft of one of the rollers 68.

The automatic means serving to actuate the hydraulic cylinder 131 is best illustrated in the 50 circuit diagram of Figure 20. In the construction shown in this figure, it will be seen that current is fed in from a suitable source by means of wires 240 and passes through a suitable transformer 241 serving to illuminate a plurality of lamps 242. A photo-electric cell 243 is associated with each of the lamps 242. It has been found preferable to provide a lamp and the photo-electric cell for each of the threads passing into the sewing mechanism and means are provided for screening the rays of the lamp from the photo-electric cell in the event that one of the threads breaks.

The circuit in which the photo-electric cells 243 are connected is substantially conventional in construction, and it will be seen that the current therefrom serves to actuate a relay 244 which, when a starting switch 245 is closed, serves to actuate the magnetically operated master switch 246 by means of a solenoid 247. This 65 master switch not only controls the circuit to the motor 200 but also serves to energize a solenoid 250 which actuates a four-way valve 248 serving to control the admission of fluid pressure to the hydraulic cylinder 131.

70 From the foregoing, it will be apparent that

as long as the lights 242 are energized and none of them are screened from their respective photo-electric cells, current will be supplied both to the motor 200 and to the solenoid 247, thus retaining the valves 248 in a position to supply fluid pressure to the hydraulic cylinder 131. In this position, it will be appreciated that the sectors 136, together with their table 137, are retained in substantially the position as shown in Figure 9, and the continuous web of felted fibrous material will be drawn through the upholstery forming machine. In the event that one of the threads to one of the stitching units should break, it will be apparent that immediately light will be cut off from one of the photo-electric cells, thus actuating the relay 244 and consequently opening the switch 246, which will not only cut off the motor 200, driving the upholstery forming mechanism, but will also serve to relieve fluid pressure from the hydraulic cylinder 131 and consequently compel the sector members 136 to move to substantially the position shown in Figure 10, thus detouring the bat fed by the pad forming unit. When the sewing machine has been repaired, it will be appreciated that the respective units thereof will be restored to substantially their original position and operation will be continued as has been described above.

It will be appreciated that the generic inventive concept presented in this application is susceptible of many and various modifications falling within the scope of the invention defined in the subjoined claims.

We claim as our invention:

1. In an upholstery forming machine, means for generating a substantially continuous web of padding material, means for feeding said padding material into an upholstery forming unit, cut-off mechanism in said upholstery forming unit for shearing off said strip of padding material when operation of said upholstery forming unit is interrupted, and means for detouring said web of padding material during the time said upholstery forming unit is not operating.

2. An upholstery forming machine comprising mechanism for forming and continuously feeding a strip of fibrous, non-woven, padding material through said machine, releasable clamping mechanism serving to lock said padding material against feed movement through said machine, stitching mechanism, means for feeding a layer of fabric finish material on top of said padding material, means for feeding a backing sheet on the under side of said padding material prior to feeding the same to said stitching mechanism, and means serving to actuate said clamping mechanism when said stitching machine is stopped.

3. An upholstery forming machine comprising mechanism for forming and continuously feeding a strip of fibrous, non-woven, padding material through said machine, releasable clamping mechanism serving to lock said padding material against feed movement through said machine, stitching mechanism, means for feeding a layer of fabric finish material on top of said padding material, means for feeding a backing sheet on the under side of said padding material prior to feeding the same to said stitching mechanism, means for feeding electric current to said stitching mechanism to operate the same, and means responsive to an interruption in said supply of current for actuating said clamping mechanism.

CLARENCE W. AVERY.
